Primary Examiner — Daniel J Domino
Assistant Examiner — Lee D Starr**(57) CLAIM**

The ornamental design for a medicament delivery device cover, as shown and described.

DESCRIPTION

FIG. 1 is a front view of a medicament delivery device cover;

FIG. 2 is a front perspective view of the medicament delivery device cover surrounding a medicament delivery device; FIG. 3 is a rear view of a medicament delivery device cover; FIG. 4 is a rear perspective view of the medicament delivery device cover surrounding a medicament delivery device; FIG. 5 is a rear perspective view of the medicament delivery device cover;

FIG. 6 is a top left perspective view of the medicament delivery device cover; and

FIG. 7 is a top rear perspective view of the medicament delivery device cover.

In the drawings, the dashed lines (- -) depict portions of the article that form no part of the claimed design. The relatively light shade lines on the surface portions indicate contour, not surface decoration, and the light shade lines form no part of the claimed design.
